FIREPLACE HEATER

Jesse Eugene Rutland, Lenox, Ga., assignor of
one-half to Jesse B. Boyett, Nashville, Ga.

Application July 29, 1938, Serial No. 222,021

4 Claims. (Cl. 126—121)

This invention relates to a heating device and more particularly to a hot air heating unit which is insertible in the present construction of a fireplace.

- 5 An object of this invention is to provide a heater structure which may be readily inserted in the opening of a fireplace and which is so constructed that the unit will readily support the fuel which is burned in the fireplace and the heat 10 generated thereby will heat air disposed in the jacket of the unit, said air then being discharged at the front and upper portion of the fireplace by means of the higher pressure of heavier cold air outside the unit.
- 15 Another object of this invention is to provide an insertible unit of this kind wherein the several parts of the units may be cast out of metal such as iron or the like and bolted or otherwise secured together, the several parts being formed 20 in jacket or hollow form so that air may freely flow therethrough for discharge into the room containing the fireplace.

A further object of this invention is to provide a unit of this kind which is adapted to receive air from outside of the building for heating 25 of the air and discharging of the heated air into the room containing the fireplace.

A still further object of this invention is to provide a unit of this kind wherein the flow of air 30 to the unit is automatically cut off when the unit is not in operation so that the cold air from the outside of the building will not flow through the jacket into the room when the fireplace is not burning fuel.

35 To the foregoing objects and to others which may hereinafter appear, the invention consists of the novel construction, combination and arrangement of parts as will be more specifically referred to and illustrated in the accompanying 40 drawings wherein an embodiment of the invention is shown, but it is to be understood that changes, variations and modifications may be resorted to which fall within the scope of the invention as claimed.

45 In the drawings:

Figure 1 is a detail front elevation of a device constructed according to an embodiment of this invention mounted in a fireplace opening, the fireplace being shown in fragmentary form.

50 Figure 2 is a sectional view taken on the line 2—2 of Figure 1.

Figure 3 is a detail top plan of the unit.

Figure 4 is a sectional view taken on the line 55 4—4 of Figure 3.

Figure 5 is a sectional view partly in top plan taken on the line 5—5 of Figure 1, and

Figure 6 is a fragmentary perspective view partly in section of the unit.

Referring to the drawings, the numeral 10 designates generally a fireplace having a rear wall 11, a throat 12 and an outlet flue 13. The fireplace 10 is provided with the usual opening 14 in the front wall 15 thereof. In order to provide a means whereby the fuel burned in the fireplace 10 may be used for the heating of fresh air drawn from the outside of the building for discharge in a heated condition in the room containing the fireplace, I have provided a heating unit which comprises a grate structure generally designated 16 as 16, a rear wall structure 17, a throat structure 18 and a discharge manifold 19. The grate structure 16 comprises an intake manifold 20 extending transversely across the opening 14 of the fireplace and this manifold 20 is adapted to have 20 an intake pipe 21 secured thereto. The pipe 21 is adapted to be extended to a point outside of the building so that fresh air may freely enter the duct or pipe 21. A damper or valve 22 is disposed in the pipe 21 at a suitable point so that, 25 as hereinafter described, the flow of fresh or cold air to the unit may be properly regulated. The manifold 20 is adapted to be cast out of metal such as cast iron and is substantially rectangular in configuration being constructed in the form 30 of a rectangular box and extends substantially across the entire width of the opening 14.

A plurality of tubular grate bars 23 are cast integrally with the manifold 20 and these grate bars 23 extend inwardly toward the back wall 11 35 of the fireplace. The grate bars 23 are spaced apart a sufficient distance so that the proper draft may be provided from below for the fuel which is engaging upon the grate bars 23 and in the present instance these grate bars 23 are also substantially rectangular in transverse section. The grate bars 23 are connected to the inner wall 24 of the manifold 20 at a point downwardly from the upper end thereof so that a considerable portion of the manifold 20 will project above the top of the grate bars 23 and thus provide a rail or front wall for keeping the fuel from dropping forwardly onto the hearth.

The rear or inner ends of the grate bars 23 are connected to and preferably cast integrally 50 with a rear manifold 25 which extends longitudinally and horizontally across the back wall 11 of the fireplace. This manifold 25 is preferably cut off on an angle to the horizontal so that the lower wall 26 thereof is relatively longer 55

than the top wall 27. A downwardly extending flange or lug 28 extends downwardly from the bottom wall 26 and provides a means for securing the rear wall structure 17 to the manifold 25.

5 The rear wall or jacket 17 comprises a rear vertical wall 29 and a front wall 30 which is spaced from the rear wall 29 and these two walls are connected together at their opposite vertical edges by a vertical wall 31. The lower end of the front wall 30 is provided with a forwardly projecting flange 32 which is adapted to rest on top of the upper wall 27 of the rear manifold 25 and the back wall 29 is provided with a flange 33 engageable against the flange 28 so that these 10 two flanges may be bolted, riveted or otherwise securely fastened together.

15 A plurality of upper heater tubes 34 are positioned in substantially the throat or upper portion of the fireplace 18 and extend forwardly and upwardly of the rear jacket 17 on substantially an angle of twenty degrees. These heater tubes 34 are preferably formed of cast iron and in the present instance are substantially rectangular in transverse section and their inner ends are secured to or integrally cast with a rear plate 35. The rear plate 35 is adapted to be secured to the rear jacket 17 by means of a plurality of rivets, bolts or other fastening devices 36. The rear plate 35 is disposed on an angle to the vertical and the 20 front wall 30 of the rear jacket 17 is preferably shorter in length than the rear wall 29 as shown in Figures 4 and 6. The front wall 30 at its upper end is preferably provided with an enlarged upper end portion 37 through which bolts or screws or other fastening members may be extended and in like manner the upper end of the rear wall 29 is provided with an enlarged portion 38 which has an inclined forward face disposed in the same plane as the plane of the forward face of 25 the enlarged portion 37.

30 The front ends of the heater tubes 34 are secured or integrally cast with a front or upper plate member 39 and this plate member 39 is secured as by fastening devices 40 to the lower inside face portion of the discharge manifold 19. The discharge manifold 19 is provided with intake openings 41 in the rear wall 42 thereof adjacent the lower end of the rear wall 42 and the front wall of the manifold 19 has a perforate 35 member in the form of a grille 43 secured thereto. The grille 43 engages in a substantially rectangular frame 44 which is carried by forwardly extending flanges or walls 45 integral with the rear wall 42. The grille 43 may be secured by 40 means of fastening members 46 engaging through the frame member 44.

45 A pair of andirons 47 are secured to the rear wall 24 of the intake manifold 20 and extend upwardly therefrom for the desired distance so as to not only give a pleasing appearance to the structure, but also to hold logs or other fuel from spilling out over the manifold 20.

50 The entire unit herein described is preferably supported in upwardly spaced relation to the floor 48 of the fireplace by means of a plurality of legs 49. These legs 49 may be constructed in two parts with an upper part 50 thereof bolted or otherwise fastened to the grate structure 23 and an extensible or lower leg part 51 provided with an elongated slot 52 through which a bolt 53 engages. In this manner the length of the leg 49 may be adjusted to provide the desired draft beneath the grate 23 and also to permit an ash pan 54 to be inserted beneath the grate 23.

55 The assembled unit comprising the grate struc-

ture 18, the jacket 17 and the heater tubes 34 are held in assembled condition by the fastening devices hereinbefore described and are also held in assembled condition by a pair of bracing bars 55 which are disposed adjacent each end thereof. The bracing bars 55 are substantially arcuate in configuration, one end of each bar terminating forwardly of the rear end of an end grate bar 23 and being provided with an enlargement or boss 56 through which a fastening member 57 engages. The intermediate portion of the arcuate brace member 55 contacts the forward wall 30 of the rear jacket 17 at a point upwardly from the lower end thereof and at the point of contact the bracing member 55 is secured to the forward wall 30 by a fastening member 58. The upper end of the bracing member 55 also has an enlarged portion 59 through which a fastening member 60 engages for securing the upper end of the bracing member 55 to an end heater tube 34. 20 A lower bracing member 61 is carried by the arcuate brace 55 and extends downwardly and rearwardly for contact with the upper side of the flange 32 at the lower end of the front wall 30. This brace 61 may be secured to the flange 30 by 25 a fastening member 62 which may also be used to secure the flange 32 to the top wall 27. An upper bracing member 63 is secured to or formed integral with the brace 55 and extends upwardly and rearwardly thereof for engagement with the 30 plate 35 and the upper end of the brace 63 may be secured to the plate 35 by one of the fastening members 36 which fasten the plate 35 to the jacket 17.

35 A damper 73 is mounted on a shaft 74 extending through the intake pipe 21 and a crank or arm 75 is secured at one end of the shaft 74. The crank 75 is connected to a second crank 76 by means of a link 77. The crank 76 is secured to a shaft 78 which has a bimetallic thermostatic 40 member 79 fixed thereto so that rotation of the shaft 78 under the action of the thermostatic member 79 will effect opening of the valve or damper 73. A crank handle 80 is secured to the opposite end of the shaft 74 and has a pin 81 in 45 slidability therethrough which is adapted to engage underneath a lug or stop member 82 fixed to the pipe 21 so that if desired the valve member 73 may be manually closed against the action of the thermostatic member 79 and held in this 50 closed position.

55 The valve member 22 is normally biased to an open position by means of a spring 69 which has one end thereof secured to an arm 67 carried by the damper or valve 22 and the other end of the spring 69 is connected to a bracket 70 fastened to the pipe 21 or any other suitable stationary part. A bracket member 68 is fixed to the pipe 21 and a valve closing member 66 in the form of a solenoid is connected to the arm 67 and operates 60 to close the grate or valve 22 when a pre-determined degree of heat has been provided in the room in which the fireplace is positioned. The solenoid 66 is connected to a thermostat 64 by means of conductors 65 and in this manner the air passing through the intake pipe 21 into the intake manifold 20 can be suitably controlled depending not only upon the temperature of the manifold 20 but also upon the temperature of the air in the room in which the fireplace is positioned.

65 In the use and operation of this unit the several parts thereof are initially assembled of a depth and width suitable to engage with the opening 14 of the fireplace and to substantially 70

75

fill all of the opening in the fireplace. The various connections between the members comprising this unit will be made air tight so that no air will leak out of the several joints and so that when the air in the hollow spaces provided in the unit has been heated such heated air will rise and be discharged through the grille 43 and form a suction by means of which cool air is drawn in through the normally open intake pipe 21. As 10 the unit becomes heated, the bimetallic thermostat 79 will gradually open the valve member 73 so as to admit cool air entering from the intake pipe 21 into the intake manifold 20. During the time that the fireplace is not in use the thermostat 15 79 will normally close the valve or damper 73 so that no cool air can flow into the intake pipe 21, the manifold 20, and the hollow circuit forming the unit, and then out through the grille 43.

However, when fuel, either coal, wood, or the 20 like, is burned on the grate member 16, the heat from the fuel will not only heat up the grate bars 23 so as to heat the incoming air which enters the grate bar 23 through the manifold 20, but will also heat up the rear jacket 17 and the heater 25 tubes 34. At the same time, the intake manifold 20 will be heated and this heat will be communicated to the bimetallic thermostat 79 so that the valve member 73 will gradually swing to an open position. After the unit has been in operation for 30 a period of time, in the event the temperature of the air in the room becomes excessive or exceeds a pre-determined degree, the thermostat 64 will become effective so as to close the circuit through the conductors 65 to the damper closing solenoid 35 66. The circuit will remain closed to the solenoid 66 until the temperature in the room has dropped to a predetermined degree whereupon the spring 69 will swing the damper or valve 22 to an open position. At this time, the circuit to the solenoid 40 66 will be broken so that the spring 69 may freely swing the damper 22 to an open position.

This device may, in the main, be cast of iron being formed of four main pieces comprising the 45 grate member 16, the rear jacket 17, the upper heating member 18, and the discharge manifold 19. These parts are preferably made of cast iron or like material so that they may be made at a relatively small cost and so that the several parts of the device will readily stand up under the heat 50 generated on the grate structure 16.

What I claim is:

1. An air heater insertible in a fireplace opening comprising a grate member including an intake manifold extending horizontally across the 55 opening, a plurality of tubular grate bars integral with said manifold, and a rear manifold integral with said bars, a jacketed rear wall rising from said rear manifold, a plurality of heater tubes extending forwardly and upwardly of said rear wall, a rear plate integral with the rear ends of said heater tubes, means securing said plate to the upper end of said rear wall, a front plate integral with said heater tubes, a discharge manifold, means securing said discharge manifold to said

front plate, and a perforate wall carried by said discharge manifold.

2. An air heater insertible in a fireplace opening comprising a plurality of tubular grate bars disposed in spaced apart parallel relation, a front 5 intake manifold integral with said bars and extending transversely of said bars, said manifold rising from the front ends of said bars, a rear manifold integral with said grate bars having an open rear portion, a hollow rear wall extending 10 upwardly from said rear manifold, means securing said rear wall to said rear manifold about the opening thereof, a plurality of upwardly and forwardly inclined heater tubes, a pair of plates integral with the ends of said tubes and maintaining said tubes in spaced apart parallel relation, said plates being disposed in parallel relation and on an oblique angle to the length of said tubes, means securing one of said plates to the upper 15 end of said rear wall, a discharge manifold engaging the other of said plates and extending upwardly therefrom, means securing said discharge manifold to said other plate, and a grille carried by the front wall of said discharge manifold.

3. An air heater insertible in fireplace opening comprising a plurality of tubular grate bars disposed in spaced apart parallel relation, a front intake manifold integral with said bars and extending transversely of said bars, said manifold rising from the front ends of said bars, a rear 20 manifold integral with said grate bars having an open rear portion, a hollow rear wall extending upwardly from said rear manifold, means securing said rear wall to said rear manifold about the opening thereof, a plurality of upwardly and 25 forwardly inclined heater tubes, a pair of plates integral with the ends of said tubes and maintaining said tubes in spaced apart parallel relation, said plates being disposed in parallel relation and on an oblique angle to the length of said 30 tubes, means securing one of said plates to the upper end of said rear wall, a discharge manifold engaging the other of said plates and extending upwardly therefrom, means securing said discharge manifold to said other plate, a grille carried by the front wall of said discharge manifold.

4. A fireplace heating unit comprising a substantially U-shaped jacketed member insertible 35 in a fireplace opening, the bight of said member engaging the back wall of the fireplace, the legs of said member extending forwardly with one leg constituting a grate, a discharge manifold carried by the other leg, an intake pipe connected 40 to said grate, and means for automatically closing said intake pipe in the non-combusting of fuel in the fireplace.

JESSE EUGENE RUTLAND.
